AEROPLANE CONTROL DEVICE

Thomas H. Crissey, New Canaan, Conn.

Application August 16, 1933, Serial No. 685,467

4 Claims. (Cl. 46—50)

This invention relates to a control device for aeroplanes and other flying machines of the toy type and has for the primary object the provision of means for adjusting the rudder and stabilizers and for automatically releasing a dummy parachute jumper or toy bomb after a predetermined flight of the machine.

With these and other objects in view this invention consists in certain novel features of construction, combination and arrangement of parts to be hereinafter more fully described and claimed.

For a complete understanding of my invention, reference is to be had to the following description and accompanying drawings, in which

In the drawings:

Figure 1 is a side elevation, partly in section, illustrating a toy aeroplane or flying machine constructed in accordance with my invention.

Figure 2 is a top plan view, partly in section, illustrating the same.

Figure 3 is a fragmentary side elevation illustrating a control lever for the steering mechanism of the aeroplane.

Figure 4 is a side elevation, partly in section, illustrating my invention applied to a flying machine of the toy glider type.

Figure 5 is an end elevation illustrating the same.

Figure 6 is a fragmentary side elevation illustrating my invention applied to a toy aeroplane of the autogyro type wherein the lifting propeller is pivotally mounted.

Figure 7 is a side elevation, partly in section, of another modification of the invention.

Referring in detail to the drawings, the numeral 1 indicates a toy aeroplane wherein the fuselage 2 is equipped with the usual steering mechanism 3 consisting of a rudder and stabilizers controlled by cables 4. A propeller 5 is arranged at the front end of the fuselage with its shaft 6 extending into the fuselage and bent to form a hook or anchoring element 7 for the purpose of connecting any suitable type of driving medium to the propeller. This driving medium may be in the form of a spring, a wound rubber band, or a small engine operated by explosive fuel or compressed air. The cables 4, at their forward ends, are connected to oppositely extended arms 8 pivotally mounted, as at 9. A control rod 10 is connected to the arms 8 at the pivot 9 and is provided with a straight portion 11 and offset portions 12. The control arm 10 is located adjacent to a feed shaft 13 suitably journaled in the fuselage and is driven from the

propeller shaft 6 by an endless belt 14 or any other form of gearing or transmission. The shaft 13 over its major portion is provided with feed threads to mesh with a nut 15 provided with spaced projections 16 engaging opposite sides of a guide rod 17 extending parallel with the feed shaft. The nut 15 may be constructed from a closely coiled element wherein the convolutions of the coil mesh with the threads of the feed shaft and the projections 16 being formed by the ends of the coiled element.

A rearwardly extending hook 18 is carried by the lower wall of the fuselage 2 to engage an eye bolt or any other similar fastener 19 carried by one end of a dummy parachute jumper 20 shaped to represent a human figure with a parachute 21 carried by the back portion. The fastener 19 is carried by the head of the dummy while the feet carry a looped element 22 held in engagement with a keeper 23 by a latch element 24 pivoted to the fuselage, as shown at 25, and operating through an opening in the bottom wall of the fuselage. The latch element 24 extends through the looped element 22 into the keeper for temporarily supporting the parachute jumper 20 in a horizontal position under the fuselage. The latch element 24 is preferably in the form of a bell crank lever, one arm portion 26 terminating in the path of the movement of the nut so that when said nut reaches a point on the feed shaft 85 adjacent one end of the latter it will engage the arm 26 and rock the latch member 24 to free the element 22 from the keeper 23 permitting the figure 20 to swing downwardly. This downward movement of the figure disengages the looped element 19 from the hook 18 and the figure may then descend free of the aeroplane, permitting the parachute 21 opening in the usual manner.

In operation, the aeroplane when adjusted for flight the feed nut 15 is at the forward end of the feed shaft 13, depressing the control rod 10 positioning the steering mechanism to cause the aeroplane to ascend when manually released by the rotation of the propeller 5. After a certain flight upwardly of the aeroplane the nut 15 engages the straight portion 11 to adjust the steering mechanism to cause the aeroplane to travel in a straight course. The nut 15 when reaching a point adjacent the rear end of the feed shaft operates the latch 24, freeing the dummy parachute jumper so that the latter may descend free of the aeroplane. While I have shown a dummy parachute jumper it is to be understood that toy bombs or the like may be connected to the aeroplane for release while the aeroplane is in flight.

Referring to Figures 4 and 5 my invention is shown applied to a toy flying machine of the glider type, the fuselage being indicated by the character 28. It is to be understood that the 5 glider type is propelled into the air for gliding by any well known medium. Mounted upon the forward end of the fuselage 28 is a supporting structure 29 carrying a guide rod 30 and also rotatably supporting a feed shaft 31. A nut 32 10 operates on the feed shaft and in engagement with the guide rod 30. The toy parachute jumper is connected to the fuselage 28 at one end by a rearwardly extending hook 33 and at its forward end by a catch 34 similar in construction 15 to the catch 24, except one end thereof is bent to form a loop 35 in which travels one of the projections of the nut 32. A forward movement or the glider in flight causes rotation of a propeller wheel 36 secured to the feed shaft. The 20 rotation of the feed shaft causes a rearward movement of the nut 32 and after a predetermined movement of the nut on the feed shaft, the projection thereof fitting in the loop 35 of the catch causes a pivotal movement of said 25 catch, freeing the dummy parachute jumper from the fuselage of the glider.

Referring to Figure 6, my invention is shown installed to a toy aeroplane of the autogyro type wherein the fuselage is indicated by the character 37. A vertical support 38 rises from the fuselage and rotatably supports a vertical shaft 39 to which is secured a horizontal propeller 40. The shaft 39 is equipped with the feed threads as in the other forms of my invention and the 35 nut 40 travels thereon. Pivoted to the fuselage 37 is a latch 41 similar to the latch 34 except the free end thereof is bent angularly, as shown at 42, and arranged in the path of movement of the nut so that after said nut travels a predetermined 40 distance on the feed threads it engages the latch and frees the toy parachute jumper from the fuselage 37.

Referring to Figure 7, a toy aeroplane of the autogyro type is shown wherein the elevating propeller is indicated by the character 43 and the shaft 44 on which the propeller is journaled is pivotally connected to a support 45, as shown at 46. The support is carried by the fuselage 47. The fuselage 47 is propelled substantially in the 50 same manner as the form shown in Figure 1, except one extension of the nut is connected to the shaft 44 by a rod 48 so that during the travel of the nut on the feed shaft, the lifting propeller 43 will be varied as to inclination and after the nut 55 travels a predetermined distance on the feed shaft it operates the latch 49 to free the dummy parachute jumper. When the aeroplane of the type shown in Figure 7 is started in flight, the nut travels from the forward end of the feed shaft towards the rear end and when the nut is 60 at the forward end it causes a tilting of the elevating propeller 43 at a proper angle to cause the aeroplane to readily rise in flight and as the

flight continues the nut adjusts the lifting propeller to maintain the aeroplane in flight in a horizontal course and as the nut reaches the rear end of the feed shaft the lifting propeller then assumes an inclined position to cause descent of the 80 aeroplane.

In all forms of my invention, the same type of feed shaft is employed and it is to be noted that the feed threads do not extend to the ends of the shaft so that when the nut reaches either 85 end of the shaft it may run off of the feed threads and idle upon the feed shaft or be retained against endwise movement with respect to the feed shaft.

While I have shown and described the preferred embodiment of my invention, it will be understood that minor changes in construction, combination and arrangement of parts may be made without departing from the spirit and scope 90 of my invention, as claimed.

Having described the invention, I claim:

1. A toy flying machine including a fuselage having a power driven propeller, a feed shaft driven by the propeller, a feed nut operated on said shaft, and a toy figure releasably supported 100 on the fuselage and freed from the latter after a predetermined movement of the nut on the feed shaft.

2. A toy flying machine including a fuselage having a power driven propeller, a feed shaft 105 driven by the propeller, a feed nut operated on said shaft, a hook carried by the fuselage, a keeper carried by the fuselage, a toy figure engaging the hook at one end, a loop element carried by the figure and engaging the keeper, and a pivoted latch carried by the fuselage and engaging the loop element and the keeper to cooperate with the hook in releasably securing the figure to the fuselage and actuated by the nut moving endwise of the feed shaft to free the figure from the 115 fuselage after a predetermined length of flight of the latter.

3. A toy glider including a fuselage, a pivoted catch carried by the fuselage, a hook carried by the fuselage, a toy parachute jumper releasably supported on the fuselage by the hook and catch, a supporting structure on the fuselage, a feed shaft carried by the supporting structure, a propeller secured to the shaft, and a feed nut on said shaft and connected to the catch for actuating 120 the latter to free the toy parachute jumper from the fuselage after a predetermined flight of the latter.

4. A toy aeroplane including an autogyro propeller, a feed shaft driven by said propeller, a 130 catch pivoted to the fuselage, a hook carried by the fuselage, a toy parachute jumper releasably supported to the fuselage by the hook and catch, and a nut operating on the feed shaft to actuate the catch for releasing the toy parachute jumper 135 after a predetermined operation of the propeller.

THOMAS H. CRISSEY.
